CLAIM

The ornamental design for a transparent display box, as shown.

DESCRIPTION

FIG. 1 is a perspective view of the transparent display box;
FIG. 2 is a front view of the transparent display box;
FIG. 3 is a rear view of the transparent display box;
FIG. 4 is a bottom view of the transparent display box;
FIG. 5 is a top view of the transparent display box;
FIG. 6 is a left side view of the transparent display box; and,
FIG. 7 is a right side view of the transparent display box.
The broken lines in the drawings are for illustrative purposes
only and form no part of the claimed design.
